FLOATING UNIT AND FLEET

Carl J. Baer, Jefferson Barracks, Mo.

Application March 30, 1935, Serial No. 13,895

7 Claims. (Cl. 114—26)

This invention relates to a boat or barge unit adapted for consolidation into a fleet for water navigation, especially suitable for use on rivers and canals.

5 This is a continuation in part of my application Serial No. 713,907, filed March 3, 1934.

The primary object of the invention is to provision of a unit which is so constructed at its bow, stern and sides that it may be combined 10 with like or similar units into fleets of different forms in such a manner that friction or water resistance will be reduced to a minimum.

Another object of the invention is to provide a particular construction so arranged that it may 15 be loaded by a water ballast to turn it on its side, thus permitting the parts normally below the water line to be exposed for cleaning, repairing and painting.

Other and specific objects will be apparent from 20 the following detail description taken in connection with the accompanying drawings.

Fig. 1 is a plan view of a unit embodying the invention;

Fig. 2 is a side elevation;

25 Fig. 3 to Fig. 10 inclusive are diagrammatical views of fleets of different forms formed of units such as are illustrated in Figs. 1 and 2;

Fig. 11 shows a fleet of units in combination with a pushing power unit;

30 Fig. 12 is a detail plan view showing means for connecting the units in a fleet;

Fig. 13 is an enlarged plan view showing the connecting means; and

Fig. 14 shows a fleet composed of a modified 35 form of unit.

The boat or barge unit is constructed in the form of a trapezoid with a longer side 1 and a shorter side 2 forming the bases of the trapezoid and straight ends 3 forming the legs thereof. 40 The units 3 meet the longer side 1 at acute angles and the shorter side 2 at obtuse angles. As specifically illustrated in Figs. 1 to 13 inclusive, each unit is in the form of an isosceles trapezoid, the ends being similarly disposed with relation to the sides. The sides and ends are preferably vertical, although they need not be so. When vertical the units fit together in fleets as illustrated in the several figures of the drawings in such a manner as to eliminate water pockets 45 between the units and thus reduce the power required for their propulsion.

Fig. 3 illustrates a simple fleet of barges combined with a tow boat 4 secured by a hawser 5 for towing or pulling the fleet. The simplest assembly for the units comprises a pair of units

designated 6 and 7 which are placed side to side with the longer side of one conterminous with the longer side of the other as shown in Fig. 3. Fig. 3 also shows an elemental form or foundation of a fleet which comprises a series of units, 5 6, 8, 9, 10 and 11, placed end to end, each unit having its sides arranged in line respectively with dissimilar sides of the adjacent unit. Thus the unit 6 has its shorter side in line with the longer side of the adjacent unit 8 and the unit 9 has its shorter side in line with the longer side of the units 8 and 10. Another line of barges 7, 8a, 9a, 10a and 11a is placed side by side with the line 10 6, 8, 9, 10 and 11, as clearly shown in the drawings. It will be apparent that the unit as illustrated provides a form which can be combined with many others to form a fleet having a pointed bow and a pointed stern.

Fig. 4 shows a fleet such as that illustrated in Fig. 3 with a number of units 12 added to the sides thereof. Fig. 5 shows a fleet such as that illustrated in Fig. 4 with further units 13 added. It will be noticed that if an even number of units are added the symmetry of the fleet can be maintained and, in any event, the streamline shape 15 can be imparted to the fleet.

Fig. 7 illustrates an arrangement of the fleet in which units 14 have been added to such a fleet as shown in Fig. 5 in such a manner as to give an enlarged head or prow. Fig. 8 shows the addition of units 16 and 17 to the fleet illustrated in Fig. 7. Fig. 9 shows the addition of units 18 to the fleet shown in Fig. 8.

It will be obvious from the foregoing that the units may be combined in a fleet in such a manner as to maintain bilateral symmetry, as well as to maintain a streamline shape. It is to be understood, of course, that particular units may be removed from a fleet without destroying a streamline form.

Particular emphasis may be laid on the fleets shown in Figs. 6 to 9 inclusive, in which the bow of the fleet is enlarged as compared to the stern to produce a form which is ovate, or more strictly, ovate-lanceolate, that is approximately the form of a torpedo. This is the streamline form which offers the least water resistance. This shape is that of a fish or whale and is sometimes referred to as amoeboid. It is the form assumed by a drop of water in falling, and by a sand bar forming 40 in a river current.

Fig. 10 illustrates the arrangement of a fleet arranged for canal transportation in which the line of units 6, 8, 9, 10 and 11 are spaced from a similar line 7, 8a, 9a, 10a and 11a by means of a 45 50 55

tow boat 19. Particular utility is presented in this assembly on account of the arrangement of the tow boat with lines of barges so spaced as to confine the current provided by the propellers 5 and thus protect the banks of the canal. In canal work towing of power boats is limited in speed on account of bank washing due to the currents generated by the propeller of the tow boat and the bow wash. With the arrangement shown in Fig. 10 10 this cutting of banks will be reduced while permitting the fleet to move at a higher rate of speed. The bow wash is reduced by minimizing the beam surface arc of the bow of the fleet.

Fig. 11 shows an arrangement in which units 15 6, 7, 8 and 8a are combined with a tow boat or pair of tow boat units 20; the tow boat or units having a pointed bow to fit in the stern formed by the units 8 and 8a. In this connection it will be observed that the power boat or unit may be 20 placed in front of the fleet to pull, as illustrated in Fig. 3 or it may be placed in the rear of the fleet to push as exemplified by Fig. 11, or, of course, it may be connected to the side of the fleet as either a pushing or pulling unit. In case 25 it is placed at the side the longer side of the unit will preferably adjoin the side of the power unit.

Attention is directed to Fig. 8 where the addition of the units 17 form forked spaces at their 30 stern ends. To prevent back suction from causing a drag on the fleet the sterns of these units 17 are spaced slightly from the adjacent units. This spacing may be accomplished with a piece 35 of rope, since a space of an inch or two is ample.

In the operation of fleets or units it will be 40 obvious that they may be loaded with cargo for delivery at different ports. The arrangement of the units disclosed herein is such that any of them may be dropped from the fleet and delivered 45 to a port and empty or loaded units may be added to the fleet at that port while maintaining a streamline form. The unit herein described is particularly adapted to be operated in fleet formation and one or more units set out at a port or 50 picked up at a port. In any event, the units of the fleet may readily be arranged whereby a new formation of the units may be put together to the best advantage for reducing the frictional action by the water and adaption to the width of the channel. Units may be added readily to accomplish this purpose ordinarily without rearranging the units that are already in the fleet.

In assembling the fleet it is preferable that 55 units of greater draft be placed in front of units of lighter draft and the deeper draft units be placed in the center rows of barges with the lighter draft units toward the outside of the fleet.

The units may be equipped with kevles or timberheads 21 at their ends and along their 60 sides in any conventional manner or form. Figs. 12 and 13 illustrate means for connecting the barge units together. More specifically a composite ratchet and chain fastening device 22 may be employed for connecting kevles or timberheads 21 on adjacent units. The device may be 65 equipped for use with or without a spring 23, said spring being made a supplemental part of the complete ratchet and chain attachment unit in order to provide flexibility between the units 70 when necessary, such as when the units are pulled by a power boat from a hawser. It also provides means for giving flexibility to a fleet where flexibility is desired. When such flexibility is not desired but where a rigid fleet is wanted a chain 75 24, shown in Fig. 13, may be used. It will be

obvious, of course, that the fleet may be connected with lines in any well known and conventional manner.

Such a unit will be ordinarily supplied with a closed top or roof 25 and provided with hatches 5 26. The units may be, and preferably are, supplied with bulkheads 27 at their ends and bulkheads 28 along the sides. The bulkheads 27 are so positioned as to form a bilaterally symmetrical loading compartment. The bulkheads 28 are of 10 particular importance because they enable the proper trimming of the barge. The bulkheads 28 are situated adjacent the vertical sides of the unit in such a manner as to form chambers along the sides which may be filled with water or other 15 ballast to trim the barge. Preferably the chambers formed by the bulkheads 28 are of such size as when filled with water ballast and the barge is empty they will tip the barge on its side permitting the cleaning, repairing and painting of 20 those parts ordinarily below water line. This is of considerable advantage because it obviates the necessity of dry docking the units for cleaning, painting and repairing.

The embodiment shown in Figs. 1 and 2, as well 25 as in Figs. 3 to 12 inclusive, shows the plan of the unit as that of an isosceles trapezoid. That is the sides are parallel and the units respectively make equal angles with a side. While the form of isosceles trapezoid is of particular utility in 30 that the many forms of fleet illustrated may be formed out of identical units, it is not necessary that the form be isosceles. This is illustrated in Fig. 14, which shows the ends respectively having 35 different angularity with respect to the sides. 40

Fig. 14 shows a fleet built up of units having such differences of angularity. In this illustration we may take for example a case where one end of the unit meets the longer side at an angle of 45° and where the other end meets the longer 45 side at an angle of 40°. The fleet consists of the units 29, 30, 31, 32, 33 and 34. Units 29, 30 and 31 are arranged end to end and are identical one with the other. The units 32, 33 and 34 are identical one with the other and are similar but 50 oppositely disposed from the units 29, 30 and 31. It is to be emphasized that, if the angularity at the bow and stern is not the same, differently constructed units (rights and lefts) of equal number are required to produce a streamline symmetrical 55 fleet.

While it has been said here that the ends meet the sides at an angle it will be understood, of course, that in actual practice the edges formed by the meeting of the sides and ends will not be sharp but will be curved to meet the requirement of actual construction and also to avoid damage to the units when the edge of one comes in contact with another unit. In speaking of shape and form it will be understood that it is the general 60 shape and form that is meant.

From the foregoing description it will be obvious that applicant has provided a boat or barge unit which can be readily assembled in a fleet formed in a streamline manner and without 65 pockets between the several units. Such a fleet reduces the cost of operation over that of conventional forms of barges by reducing the power required for its towing.

A fleet composed of these units has a decided 70 safety feature over one composed of conventional barges. In case an obstruction is encountered the impact will cause a wedging action between the units, snapping the lines, but no further damage will be done.

With the use of these units having vertical sides and ends and arranged in a fleet without pockets a fleet of smaller area is required to carry an equal tonnage. That is to say, in comparison 5 with a fleet of the same over-all area composed of conventional river scows having inclined ends, a fleet composed in accordance with this invention will handle a very much greater tonnage. This is an advantage not only in saving of power 10 but also in having of space in locks and channels and in ease of handling.

Since the essential features of the invention are pointed out in the appended claims it is obvious that various changes may be made in the 15 details of construction, within the scope of the claims, while retaining the benefits and advantages of the invention.

I claim:

1. A boat unit adapted to be placed in contiguity with others of its kind to form a barge fleet and having the form of an isosceles trapezoid, the sides of the unit forming the bases of the trapezoid and the ends the legs of the trapezoid.
- 25 2. A bilateral symmetrical fleet of barge units each having parallel sides and straight ends with the sides and ends forming a trapezoid, the sides being the bases of the figure and the ends being the legs thereof.
- 30 3. In a fleet of barge units a plurality of like units arranged end to end each in the form of a trapezoid with the sides forming the bases of the trapezoid and the ends the legs thereof, each of

said units having its sides arranged in line respectively with dissimilar sides of the adjacent unit or units.

4. A boat unit adapted to be placed in contiguity with others of its kind to form a barge fleet and having parallel sides and straight ends with the sides and ends forming a trapezoid, the sides being the bases of the figure and the ends being the legs thereof.

5. A boat unit adapted to be placed in contiguity with others of its kind to form a barge fleet and having parallel sides and straight ends with the sides and ends forming a trapezoid, the sides being the bases of the figure and the ends being the legs thereof, and both ends meeting 15 one side at acute angles respectively and meeting the other side at obtuse angles.

6. In a fleet of barge units a pair of similar units each having parallel sides and straight ends forming a trapezoid, the sides being the bases of 20 the figure and the ends being the legs, the two units being assembled with the side of one conterminous with the like side of the other.

7. A floatable barge or boat unit adapted to be placed in contiguity with others of its kind to 25 form a barge fleet and having the top and bottom identical in shape and size with vertical sides and ends, the plan of the top and bottom having the form of an isosceles trapezoid with the two angles formed by one side with the two ends 30 equal.

CARL J. BAER.
